Paul W. Schreyer
ATTORNEY

UNITED STATES PATENT OFFICE.

CHARLES F. H. BOHNHARDT, OF LOS ANGELES, CALIFORNIA.

LIQUID-SEAL EXPANSION ROOF.

Application filed February 1, 1928. Serial No. 251,195.

My invention relates to the art of oil storage with especial reference to a tank roof.

An object of my invention is to prevent the loss of vapor through the daily breathing of such tanks caused by variations in temperature between night and day. As the temperature increases the vapor in the tank expands and escapes through a relief valve; conversely as the tank cools at night, air is drawn into the tank through a vacuum relief valve. Such breathing causes large evaporation losses. By providing a tank with sufficient expansibility to accommodate this volume change, breathing and evaporation losses are stopped.

Other objects and advantages will be apparent from the following description of a preferred embodiment of my present invention, reference being made to the accompanying drawing, in which:

Figure 1 is a section through a tank showing one manner of applying my liquid seal expansion roof.

Figure 2 is a section through a tank showing a second manner of applying the same.

Figure 3 is a detail of the liquid seal.

Figure 4 is a detail of a liquid seal relief valve.

In the application of my invention I provide around the top of the tank shell a continuous trough designated by numeral 1. This trough is made in sections, each section a single piece of steel bent to the shape shown and welded to the tank shell 2 as at 3. It is desirable to have the outer peripheral wall 5 of this trough about as high as the top of the tank shell. Suitable bracing to support the trough is shown at 4.

The tank roof 6 extends beyond the tank shell to reach about the center of the trough. A downward extending skirt 7 is non-leakably secured to the edge of the roof and dips into the trough. The trough is filled with water and, as skirt 7 extends below the water level a gas tight joint is made between the tank shell and the roof. The roof floats on the vapor in the tank. The depth of the trough is determined by the expansibility required. The pressure necessary to float a roof of usual weight is only a few inches of water.

Where a tank is large it is economical to use the arrangement shown in Figure 2. The trough is secured in the roof and the center part of the roof is equipped with a skirt extending into the trough as before. By pro-

viding a deeper trough and a longer skirt the same degree of expansibility can be obtained as is obtained in the first arrangement, the moving parts being smaller.

It is necessary to prevent the roof from rotating. I accomplish this by providing two or more closed tubes 9 non-leakably secured to the tank roof, into each of which a pipe column 10 extends. These columns are braced within the tank and prevent the roof from rotating, yet allow it to move vertically.

When the roof is at its lowest position it rests on the columns 11 which are braced within the tank.

It is to be noted that the pressures in the tank are very nearly constant. A pressure relief valve operated by change in pressure would not function here, but by providing a valve as in Figure 4 which depends on the position of the roof to operate it this difficulty is eliminated. This valve consists of a cup 12 secured to the tank roof, open end down and extending into a second cup 13 secured to the tank bracing, open end up. A pipe 14 welded in the bottom of cup 13 extends vertically upwards. Cup 13 is filled with water or oil and is so positioned that the cup 12 is withdrawn from the fluid in cup 13 before the skirt 7 breaks its seal in the trough 1. Vapor then escapes through pipe 14 to a vapor recovery system or simply to the outside of the tank. In this manner the roof is prevented from over-traveling and the vapor is not permitted to blow through the roof seal.

The means above described for sealing the vapor outlet is desirable for several reasons; it is reliable, free from working parts and is absolutely gas tight. However, there are conditions in which such a valve would not be entirely satisfactory. Where any liquid in the vapor lines except the condensate of the vapor itself is undesirable such a liquid sealed valve would not do. For such installations I contemplate the use of other valves. Any valve which can be operated by the movement of the roof is suitable, such valves as the ordinary stock cock and others answer this requirement.

My present invention can be very economically applied to old tanks. By cutting the old roof free from the tank shell and providing the trough 1 and the skirt 7 the old roof can be used as an expansion roof. Other slight changes are necessary but great economy is effected by using the old roof.

By weighing my expansion roof with suitable ballast, pressures greater than atmospheric can be maintained on the vapor in the tank. In storing liquids with high vapor pressure this would materially reduce the volume of vapor formed.

The principle of my liquid seal expansion roof can be utilized on all manner of storage tanks and reservoirs for storage of other liquids than oil, and I do not limit myself to the specific embodiments herein described except as defined in the following claims.

I claim as my invention:

1. In vapor disposal means for an oil storage tank equipped with a vapor sustained roof, a relief valve comprising: a first cup stationarily secured within said tank, open end up, said end being higher than the surface of said oil; a second cup secured to the roof of said tank, open end down, and adapted to enter said first cup; and a tube passing through the bottom of said first cup and secured thereto, said tube extending upward

within said cups to substantially the level of the top of said first cup, the opposite end of 25 said tube communicating with said vapor disposal means; said first cup being filled with a liquid into which said second cup dips to form a gas tight seal between said tube and the interior of said tank.

2. In vapor disposal means for an oil storage tank equipped with a vapor sustained roof, a relief valve comprising: a pair of 30 cups; the larger of said cups stationarily secured within said tank, open end up, said end being above the surface of said oil and filled with a liquid; the smaller of said cups secured to said roof, open end down and adapted to enter said lower cup; and means 35 for conveying tank vapors from within said smaller cup when said roof has lifted said smaller cup from the liquid in said lower cup.

In witness that I claim the foregoing I have hereunto subscribed my name this 27th day of January, 1928.

CHARLES F. H. BOHNHARDT.
